UNITED STATES PATENT OFFICE.

WALTER WOLFF, OF CHICAGO, ILLINOIS.

SASH WEIGHT.

Application filed March 16, 1927. Serial No. 175,667.

My invention relates to improvements in window or sash weights, being more particularly concerned with sectional sash weights or sash weights which are adjustable in weight.

While my invention may be used with any system of ropes and pulleys, it is of particular importance and advantage when used with that type of installation where one combined sash weight is employed in each weight box, the rope being passed through a pulley aperture in the weight and through the window pulleys and being affixed at each end to a different sash. With this system of installation, a single sash weight is adapted to lift one side of two separate sashes and only half as many weights are required per sash, but in order to provide the same amount of lifting force on the sashes, the weights should be made twice as heavy.

As the cross section of the weight is ordinarily limited to a size which will pass through the weight box opening, which is usually of the same width as the thickness of a sash, the weights of the prior art can not be made as heavy as they should be without unduly increasing their length and correspondingly limiting the length of travel in the weight box. In other words, if the weight is made heavier, it will become too long so that it will hit the bottom of the box before the window is fully opened. The length of travel of each weight is the length of the box below the pulleys, diminished by the length of the weight itself, and it is therefore evident that the limitation in cross section of the weight imposed by the size of the weight box opening and the limitation in length which is imposed by the requirement for the length of travel which will completely open the window, prevent the employment of weights of the most desirable size and the full utilization of the space in the weight box.

One of the objects of my invention is the elimination of the foregoing difficulties by the provision of a sectional sash weight which may be installed in the old type of window frames without any changes in the window frames, and which will provide a maximum of weight per running inch of travel, fully utilizing all of the space in the weight box.

Another object of my invention is the provision of a sash weight of the class described having a plurality of sections which are

divided vertically for the purpose of taking advantage of the full width of the weight box and, at the same time, enabling the convenient and easy attachment of said sections to each other through the small box openings in the weight boxes of old windows.

Another object of my invention is the provision of a sash weight of the class described having means to compensate for the difference in weight between the upper and lower sashes, so that where one of these is considerably heavier than the other, I am enabled to use a weight of sufficient size to properly balance the heaviest window and, at the same time, prevent this heavier weight from moving the lighter sash from its adjusted position when such movement is not desired.

Other objects and advantages will appear more fully from the following description and from the accompanying drawings in which similar characters of reference indicate similar parts throughout the several views.

Referring to the drawings:

Fig. 1 is an elevational view of a window equipped with my sash weights.

Fig. 2 is an enlarged, detailed, cross-sectional view on the line 2-2 of Fig. 1.

Fig. 3 is an enlarged, elevational view of my sash weights, showing the compensating arrangement of the pulleys.

Fig. 4 is a side, elevational view of weights similar to those shown in Fig. 3.

Referring to Figs. 1 and 2, 10 indicates in its entirety the window frame, which is provided with the upper sash 11, the lower sash 12, both said sashes being adapted to slide in the usual guides provided by the outer stop 13, the inner stop 14, and the parting bead 15.

The window frame 10 is provided with the usual pair of pulleys 16 and 17 at the top of each side of the frame, and with the usual weight box 18 extending along each side of the frame below the pulleys 16 and 17.

After the trim 19 of the window frame has been nailed in place, the weight boxes 18 are effectively closed from the front and are accessible for the installation of weights or the change of weights only through the usual weight box opening 20 which may be provided in either or both of the guides for the sashes. This weight box opening usually consists of an opening sawed in the board 21 of the frame with a beveled cut 22, so that

the cover 23 of this opening will not fall into the weight box but may be secured in place by a small screw or brad.

In order that the weight box may be accessible without removing the parting bead 15, the opening 20 is usually limited in its width to the thickness of the sash, but the length of the weight box opening 20 is limited only by the length of the sash and it is usually 10 made of approximately the same length as the old type of round cast iron sash weights.

While I have shown my adjustable sash weight as provided with pulleys and with a single weight on each side of the window frame, I desire to be understood that my invention may be employed also where it is simply desired to fasten the end of the sash cord to the weight. In such case, the cord may be tied about the central pulley and the 20 number of weights used will depend upon the usual method of installing ropes and weights. However, my sash weight is particularly adapted to be used in the system shown in Fig. 1, wherein a single sash cord 24 is employed on each side of the window.

One end of the sash cord 24 is attached to the left edge of the sash 12 in the usual manner, the cord passing from the sash 12 over the forward pulley 17, thence down the 30 weight box 18, around the pulley 34 of the sash weight, thence upward in the weight box over the rear pulley 17, the other end of this cord being attached to the left edge of the upper sash 11 in the usual manner. The 35 other sash cord 24, with its weight, is attached to the sashes 11 and 12 at their right edges in a similar manner to that just described, and it will thus be observed that the sashes 11 and 12 are supported at each edge 40 by a single sash weight.

Referring to Figs. 3 and 4, 26 indicates in its entirety my combined sash weight, which comprises an upper supporting section 27 and a plurality of lower removable sections 45 28, 29 and 30, which are divided along a vertical line 31, preferably centrally located, so that the weights will be properly balanced.

The upper section 27 may be a cast metal 50 member having substantially rectangular sides and a transverse slot 32 located in its upper edge and of slightly greater width than the pulleys 33 to 35, which are to be located therein. The slot 32 should be of sufficient depth to receive the pulleys 33 to 35, and the supporting section 27 is provided 55 with a plurality of regularly spaced apertures 36 which are adapted to receive the transverse pins 37 to rotatably support the pulleys 33, 34 and 35 in the slot 32. The apertures 36 may be slightly countersunk at each end and the pins 37 riveted over at each end to permanently assemble these parts.

65 The supporting section 27 has its lower

edge 38 concavely curved, conforming substantially to the shape of a cylinder, and the upper edges of the removable sections 28, 29 and 30 may be complementarily shaped to fit within the concave surface 38 by providing an upper edge 39 shaped like the exterior of a cylinder. 70

In order to provide for a slight latitude of rotative movement between the edges of these sections, the curved surface 39 at the upper edge of the removable sections should preferably be extended downward a slight distance below the edges 40 of the upper section to which they are attached. Thus the surface 39 continues downward as at 41, 80 leaving a slot at each side when these sections are attached together so that they may be slightly rotated relative to each other for a purpose further to be explained.

The lower edges 40 of the upper sections, and the cylindrical portions 39 of the lower sections, are provided with registering apertures 42 and 43, respectively, which are adapted to receive a pin 44 of a length equal to the thickness of these sections or slightly less than the same, so that the pin may not project therefrom. 85

In order to maintain the pin 44 in the position shown in Fig. 4, the apertures 42 may be made a very close fit therewith and for this purpose they may be drilled rather than cast. However, in order to provide a sash weight which requires no machine work, the apertures 43 in the upper edges of the lower sections are preferably made of the shape 90 shown in Fig. 3, having upwardly converging walls 45 so that when the pin 44 is in place and the lower sections 29 and 30 are pulling downward, due to their weight, the walls 45 will wedge upon the central portions of the pins 44 and maintain these pins in their proper position. By means of the cylindrical curvature of the surfaces 38 and 39, I am enabled to place the respective sections of the sash weight together with the 95 apertures 42 and 43 in approximate alignment, and by rotating the cylindrical portion 39 within its complementary surface 38, the apertures 42 and 43 may quickly be brought into exact alignment so that the pin 44 may 100 be easily inserted.

In this operation, the increased size of the apertures 43 at their bases greatly aids the insertion of the pin 44, and when the pin has been located, as in Fig. 4, the wedging 105 action of the apertures 43, and the co-operation of the surfaces 38 and 39, effectively prevents any axial movement of the pins 44.

In order that the pins 44 may be inserted or removed from the weights while they are 115 in the weight box, and in order that this operation may be performed through the weight box opening 20, the apertures 42 and 43 are preferably located close to the center 120 of the supporting section 27 and at the 130

upper, inside corners of the lower sections 28, 29 and 30. It will thus be observed, in Fig. 2, that the pin of the section 29 is directly in front of the weight box aperture 20.

The pin of the section 28 may be brought into alignment with the weight box opening 20 by swinging the weight toward the right an amount which is permitted by the necessary play or clearance between the sash weights and the walls of the weight box; namely, the distance between the right edge 46 of the weight 29 and the right edge 47 of the weight box.

15. It will thus be observed that, although the points of attachment are eccentrically located upon the lower weight sections, they are symmetrically located with respect to the upper or supporting section, and when a pair 20 of weights 28 and 29 are supported upon the upper section, as shown, the shape of the combined sash weight is symmetrical with regard to the location of the pulleys 33, 34 and 35.

25. The details of the lower edges 48 and 49 of the sections 28 and 29 may be exactly similar to the lower edge surface 38 of the upper supporting section, with the exception that the round apertures 42 are symmetrically located in the lower, inside corners of these edges.

It will be observed, also, that the upper edge of additional sections 30 may be formed exactly similar to the upper edge of the sections 28, and 29 and that any number of sections 28, 29 and 30 of exactly similar form may be readily attached below each other to make the sash weight any convenient size permitted by the size of the 40 weight box.

The weight sections 28, 29 and 30 may be identical for use on the left or right side, thereby eliminating the necessity for making more than two different kinds of sections, and ordinarily a sufficient variation in weight may be procured by adding two of the sections at once, as shown in Fig. 3. However, if it is desired to add a single section below the upper weight section 27 50 or below a pair of sections 28 and 29, such a section may be provided with a pair of apertures like the apertures 43, symmetrically located near the center of the top edge in such manner that a pair of pins may be used to join such section to the top section 27 or any lower sections, such as 28 and 29. A single section may thus be supported in balanced position, either below the top section or any succeeding pair of sections.

60. A very important feature of my invention is the size of the supporting section 27 and any other lower sections used relative to the size of the weight box 18 and relative to the size of the weight box opening 20.

65. Referring to Fig. 2, it will be observed

that the width of the supporting section 27 is but slightly greater than the width of the weight box opening 20. As it is always necessary to provide some clearance on all sides of the sash weight, the thickness of 70 these sections is slightly less than the depth of the weight box 18, and it will be observed that this clearance, relative to the depth of the weight box, permits the insertion of an upper supporting section 27 which is slightly 75 wider than the opening 20. In the operation of insertion, the section 27 is inserted with one edge first, the other following after the first edge has been moved over into the weight box.

The width of the removable sections 28, 29, 30, etc., should preferably be slightly less than the width of the opening 20, and is limited by the amount of clearance necessary to swing the apertures in the section 85 28 over where they align with the opening 20. It will thus be observed that the combined sections 28 and 29, together with any sections which may be attached below them, are adapted to utilize to the fullest extent 90 the width and depth of the weight box 18, leaving only the necessary clearance. As these sections may be made of the maximum permissible width, they will provide the weight required without taking up so much 95 of the length of the weight box, thereby greatly increasing the length of travel of the weights.

The method of installation of my sash weights in existing window frames is as follows:

The old weights and ropes having been removed, a fish tape may be inserted at the pulleys 17, and after the cord has been passed through the pulley 34, the ends of the 105 rope may be pulled up over the pulleys and attached to the sashes in the usual manner. The upper supporting section 27 may then be inserted through the aperture 20, as previously described, and by swinging this 110 section to the right, the lower section 28 may be attached and a pin inserted through its aperture 42. During this operation, the swiveling feature of the surfaces 38 and 39 will greatly aid in the alignment of the 115 apertures.

The section 29 may then be attached in a similar manner by a pin 44 through its aperture and through the section 27 and the desired number of other sections may be 120 attached in a similar manner below the sections 28 and 29 to make the sash weights of any desired size. As the weight moves upward when one sash is lowered and downward when the other sash is lowered, the 125 ropes should preferably be of such length that the weights are located substantially in the center of their travel.

In order to compensate for differences in weight between the different sashes, my up- 130

per supporting section 27 is provided with a plurality of pulleys 33, 34 and 35. As the pulley 34 is centrally located, my sash weight may be employed in the usual manner, shown in Fig. 2, using only one pulley. But when one of the sashes is of considerably greater weight than the other, the rope 24 is preferably passed through the pulleys in the manner shown in Fig. 3. It will be observed that the rope 24 passes under the pulley 33, over the pulley 34, and under the pulley 35, and as an odd number of pulleys are provided, the rope emerges from the top of the section in the same direction as when a single pulley is used.

I have found that with the arrangement shown I am enabled to provide sash weights in the system shown in Fig. 1, which are of a weight adapted to substantially balance the weight of the heaviest sash but, at the same time, the resistance added by this arrangement is such that this heavier weight will not, of itself, actuate the lighter sash. In such case, I can even employ a sash weight which is heavier than the lighter sash, but by means of the arrangement shown, the lighter sash, as well as the heavier sash, will remain in any adjusted position and will be balanced with a single weight of adequate size so that both will move easily, when desired.

It will thus be observed that I have invented a sectional sash weight which utilizes all of the space available in the weight box, giving more weight, per running inch, than any of the weights of the prior art, and that this sash weight can be installed in existing windows through the usual small aperture provided in weight boxes. My sash weight is also adapted to be used simultaneously with sashes of greatly different weight, as it includes means for compensating for the difference in weight between such sashes.

Since my weights are constructed of cast metal, there is considerable tolerance or clearance between the respective weights. The symmetrical location of the holes in the upper weight section supports the lower weights in such manner as to form a balanced structure. The eccentric location of the apertures in the upper corners of the lower weights causes all of the lower weights to swing toward each other, each lower weight being counter-balanced by the opposed weight. At the same time, the pivotal connections provided by pin and aperture permit the lower weights to swing down although the narrower upper weight may be tilted by frictional forces acting upon it. My sash weight is therefore adapted to hang centrally in a box no matter whether the upper weight section is tilted and no matter whether the point of attachment to the upper weight section may be slightly out of center.

While I have illustrated and described a specific embodiment of my invention, many modifications may be made without departing from the spirit of the invention, and I do not wish to be limited to the precise details set forth but desire to avail myself of all changes within the scope of the appended claims.

Having thus described my invention, what I claim as new and desire to secure by Letters of the United States is:

1. In a sash weight, the combination of means for support of said weight by a rope, with a plurality of sash weight sections of a size adapted to pass the weight box aperture and supported on said means side by side to use substantially the full width of the box.

2. In a sash weight, the combination of a main weight section having a pulley therein and having a slotted base, with a plurality of narrower sections centrally supported from said main section side by side, said narrower sections having tops receivable in said slotted base and said sections having registering apertures, said apertures being located where accessible from the weight box opening, pins for securing the same together, and means for holding said pins in place comprising upwardly converging walls in the apertures at the tops of said narrower sections.

3. In a window, the combination of a frame having guides, weight boxes, upper and lower sashes of different weights, with a sash weight system comprising a pair of pulleys at the upper part of each side of the frame, a pair of ropes, each having an end attached to each sash, said ropes having closed loops in the weight boxes, and a weight in each box having a plurality of pulleys, said ropes passing alternately on opposite sides of said pulleys.

4. In a sash weight, the combination of a main weight section having a pulley therein and having an arcuate base, with a plurality of narrower sections centrally supported from said main section side by side, said narrower sections having complementary arcuate tops and said sections having registering apertures transverse to said arcuate base, and a pin passing through said sections for securing the same together.

5. In a sash weight, the combination of a main weight section having a pulley therein and having an arcuate base, with a plurality of narrow sections centrally supported from said main section side by side, said narrower sections having complementary arcuate tops and said sections having registering apertures transverse to the axis of said arcuate tops, said apertures being located where accessible from the weight box opening and said weight sections being adapted to utilize the full cross-section of the

weight box, and pins for securing said sections together.

6. In a sash weight, the combination of a weight box having an aperture extending only across a part of the width of the box, a sash weight having means for its support by a flexible member, and a plurality of weight sections depending from said weight side by side to substantially fill the cross-section of the weight box and of a size adapted to pass said aperture.

7. In a sash weight, the combination of a main weight section having means for its support by a flexible member, and having a transverse slot in its base, with a plurality of other sections having similar slots in their bases and having their tops formed to be received in the slot of said main section and means for pivotally joining said sections.

8. In a sash weight system the combination of a relatively narrow main weight section with a plurality of lower weight sections pivotally depending from said main weight section and carried thereby side by side to form a lower weight section of a size adapted to substantially fill a weight box.

9. In a sash weight, the combination of a supporting weight section, with lower

weight sections carried side by side from said supporting section, said lower sections being provided with attaching means eccentrically located on said lower sections to cause the same to swing toward each other.

10. In a sash weight assembly, the combination of a pair of sashes, guides therefor, flexible means supporting said sashes and counter-balanced by a sash weight, said sash weight being provided with a pulley supported by said flexible means and said sash-weight being provided with a plurality of sections, each eccentrically supported and counter-balanced by an opposed section eccentrically supported.

11. In a window weight system, the combination of flexible means with sashes of unequal weight attached one at each end of said means, a floating main weight section having friction means for resisting movement of said weight relative to said flexible means, and a pair of lower weight sections eccentrically pivoted on said main section to counter-balance each other.

In witness whereof, I hereunto subscribe my name this 14th day of March, 1927.

WALTER WOLFF.
